UNITED STATES PATENT OFFICE.

JAMES H. PREATER, OF BROOKLYN, NEW YORK, ASSIGNOR TO WRIGHT
GILLIES & BRO., OF NEW YORK CITY.

DESIGN FOR CANISTERS.

Specification forming part of Design No. 7,190, dated February 17, 1874; application filed February 3, 1874.
[Term of Patent 7 years.]

To all whom it may concern:

Be it known that I, JAMES H. PREATER, of Brooklyn, in the county of Kings and State of New York, have invented or produced a Design for Canisters, of which the following is a specification:

The shape and configuration of this canister are represented in the accompanying drawing, in which—

Figure 1 is a front view, and Fig. 2 is a horizontal section.

The general configuration of the canister is cubical; but the lid *a* is curved and applied at the upper front portion of the canister, where the same is made as a section of a cylinder, as before usual.

The front *b* is flat, or nearly so, and between the front *b* and sides *c c* there are coves formed by the segments *d d*, and within these coves are the columns *e e* resting upon the bottom *f*,

and extending to the overhanging top plate *g*. These columns are represented as made with square bases *h*, but the shape of the base and the column may be varied.

The design of the shape and configuration of this canister is highly ornamental, and to the same I give the name of the "Colonade." There may be an ornamental knob above the column resting upon the top plate.

I claim as my invention—

The design of the canister, consisting of columns in coves at each side of the front, as set forth.

Signed by me this 28th day of January, A. D. 1874.

JAMES H. PREATER.
